HARRY H. RALPH, OF PHILADELPHIA, PENNSYLVANIA, ASSIGNOR TO BOILER WATER PURIFIER COMPANY, OF PHILADELPHIA, PENNSYLVANIA, A CORPORATION OF DELAWARE.

PURIFIER FOR STEAM-BOILERS.

1,120,405.

Specification of Letters Patent.

Patented Dec. 8, 1914.

Application filed April 14, 1914. Serial No. 831,887.

To all whom it may concern:

Be it known that I, HARRY H. RALPH, a citizen of the United States, residing at the city of Philadelphia, in the county of Philadelphia and State of Pennsylvania, have invented certain new and useful Improvements in Purifiers for Steam-Boilers, of which the following is a specification.

The principal object of the present invention is to provide a feed-water purifier for steam boilers of simple, efficient and comparatively inexpensive construction whereby raw water, as it is fed to the boiler, shall have eliminated therefrom to a great degree, certain objectionable dissolved solids, as, for instance, silica, oxid of iron and alumina, lime and magnesia.

A further object of the present invention is to provide means upon the feed-water purifier for recovery from the surface of water within the boiler during the blow-off, certain refuse matter or scum that has escaped from the purifier.

Other objects of the invention relate to general details of construction and arrangement of parts.

The invention consists of the improvements hereinafter described and finally claimed.

30 The nature, characteristic features and scope of the invention will be more fully understood from the following description, taken in connection with the accompanying drawings forming part hereof and in which:

35 Figure 1, is a view in side elevation, partly sectioned of a steam-boiler equipped with a purifier embodying the invention, Fig. 2, is a view in central section, drawn to an enlarged scale, of the purifier embodying the invention. Fig. 3, is a plan view thereof, Fig. 4, is a view in section drawn to an enlarged scale and taken upon the line 4—4 of Fig. 2, and Fig. 5, is a detail view, in section, of a check valve hereinafter referred to.

40 In the drawings and referring more particularly to Fig. 1, there is illustrated an ordinary horizontal tubular boiler 1, contained within which is the feed-water purifier 2, of the invention. As shown, the purifier consists of three sections 3, 4 and 5, bolted together as at 6, to form a casing. The number of sections, however, is immaterial. Leading to the purifier 2, from a

necting to the section 3, is a feed-water inlet connection 7, provided with a valve 8. This connection 7, is of light weight tubing and is coiled as shown at 9, in Fig. 3, within the boiler 1, the number of coils depending upon the boiler horsepower. These coils provide additional heating surface to the feed inlet, so as to secure an efficient precipitation of solid matters or sediment. The opposite end of the purifier 2, or the section 5, thereof, has leading therefrom a pipe 10, having a valve 11. This pipe may be connected with the valved blow-off 12, of the boiler 1. As shown in Fig. 4, the cross section of the body portion of the purifier is substantially pear-shaped and adjacent the upper part and upon each side thereof are a series of oppositely disposed openings 13, and 14, of which each section of the purifier is provided with four, although the number of openings are immaterial. Of these openings those designated 13, have leading therefrom pipes 15, and 16, of which the pipe 15, is shown as extending rearwardly and parallel with the sides of the purifier and the pipe 16, as extending forwardly in like manner, the pipes 15, and 16, terminating in funnel-like members 17, which are horizontally disposed as shown. The coil 9, is also provided with a funnel-like member 17, horizontally disposed. The remaining openings of the purifier or those designated 14, are provided with movable valves or flaps 18, shown as being hinged to the purifier 2. As shown in Fig. 4, the purifier body is provided with lugs 19, having bolt openings that register with similar openings in lugs 20, of the valves 18. Bolts 22, acting as pintles serve to afford hinged relation for the parts. The valves 18, may be provided with stops 22^a, adapted to abut against the walls of the purifier 2, to limit their outward swing. Adjacent the feed-water inlet 7, and preferably immediately to the rear of the openings 13, is a baffle plate 23, shown as extending from the top-most portion of the purifier downward to within a short distance of the bottom thereof.

45 In practice, it is endeavored to keep the water line within the boiler 1, even with the funnel tops 17, and 17^a, above described, so that the water outlet openings 14, are consequently below the water line, and it may be here remarked that normally pressure

within the purifier 2, is slightly in excess of pressure within the boiler. In feeding raw water, which usually contains silica, oxid of iron and alumina, lime and magnesia, to the 5 boiler 1, it is led to the purifier 2, and impinges against the baffle plate 23. The sediment in the water, caused by the precipitation of the above solids as they pass through the heated coils 9, is directed to the bottom 10 of the purifier and caused to settle within the chamber 24, that extends along the base thereof. The water that has been freed of these solids rises in the purifier and finds its way to the boiler interior through the 15 openings 14, pressure within the purifier being sufficient to overcome the gravity flaps 18, and permit them to move outward for the purpose. During the procedure of feeding water to the purifier the flaps of the 20 check valves 25, which are provided the pipes 15, and 16, and the short extension 26, from the coil 9, which carries the funnel-like member 17^a, are all closed to prevent the admission of scum to the purifier.

25 When it is desired to rid the purifier of sediment, use is made of the blow-off connections 10, and 12, the valve 8, of the feed inlet 7, being closed and the valve 11, of the blow-off pipe 10, opened. During the blow-off, the baffle-plate 23, serves to direct the force of steam and water that passes from the boiler 1, through the funnels 17, downward to the bottom of the forward end of the purifier and thence rearward along 30 through the chamber 24, to the pipe 10. In this way, the bottom of the purifier is cleaned from end to end. During the blow-off, there is necessarily present within the purifier a certain amount of agitation calculated to raise the sediment in the bottom 35 thereof and which it is desirable not to have find its way to the boiler interior. In this respect, the gravity flaps 18, act in this capacity and during the blow-off remain closed 40 because the amount of pressure within the purifier is slightly less than pressure within the boiler at this time. In addition to the fact that these flaps by being closed prevent the egress of sediment to the boiler 45 during the blow-off, they further serve to direct the force thereof toward the bottom of the purifier. Regarding the blow-off period, it may be further stated that the funnels 17 and 17^a, serve at this time to gather 50 or collect from the surface of the water within the boiler any scum that may be present and deposit the same by way of the openings 13, within the purifier, from which it escapes during the blow-off by way of the 55 pipe 10. It will, of course, be understood that this is possible since pressure within the purifier is lower at this time than pressure within the boiler and consequently the flaps of the check valves 25, open, see Fig. 60 5. It is to be noted in this connection that

the funnel 17^a, by its quick intake of boiler water, purges the coils of any sediment present therein.

What I claim is:

1. In apparatus of the character described 70 a steam boiler, a feed-water purifier including its complemental feed inlet located within the boiler, and below the normal water level thereof, valved ports arranged along each side of and throughout the entire length of 75 said purifier for normally permitting water as it goes through the purifier to egress to the boiler at substantially the same level as the point of admission, and means for closing the valves of said ports to temporarily interrupt such passage of water.

2. In apparatus of the character described 80 a steam boiler, a feed-water purifier, including its complemental feed inlet and points 85 to egress located within the boiler and below the normal water level thereof, means for maintaining pressure within the purifier slightly in excess of pressure in the boiler, means for permitting water as it flows through the purifier to pass through said 90 points of egress to the boiler at substantially the same level as the point of admission, and means for reducing the amount of pressure within the purifier to a point lower than pressure within the boiler, whereby the 95 points of egress are automatically closed.

3. In apparatus of the character described 100 a steam boiler, a feed-water purifier including its complemental feed inlet located within the boiler, and below the normal water level thereof, means for maintaining pressure within the purifier in excess of that within the boiler, means upon opposite sides of and operatively connected with the purifier for delivering scum from the water surface within the boiler to the purifier, a series 105 of valves complemental to egress openings arranged upon each side of and throughout the entire length of said purifier, for normally permitting water to pass from the purifier to the boiler and means for reducing pressure within the purifier to a point below that of the boiler to cause the scum delivering 110 means to operate and for interrupting the egress of water from the purifier to the boiler.

4. Apparatus of the character described 115 comprising a hollow casing having a horizontally arranged inlet connection, a baffle plate immediately adjacent the inlet and extended from the top of said casing downward to within a short distance of the bottom thereof, and a series of valves complemental to egress openings arranged upon each side of said casing throughout the entire length thereof.

5. A water purifier of the class recited 120 comprising a hollow casing provided throughout its entire length with a series of openings, movable covers for some of said 125

openings, pipes terminating in funnel-like extensions for other of said openings, a horizontal feed inlet for the casing and a baffle plate immediately adjacent the inlet and 5 extending from the top of said casing to a point near the bottom thereof.

6. In combination a steam boiler, a feed-water purifier within the boiler and below the normal water level thereof, normally 10 passing water from a series of valved ports arranged along each side of the purifier opening directly into the boiler at substantially the same level as the point of admission, said point of admission being adjacent 15 the top of the purifier, means for blowing off the purifier and means for interrupting the passage of water from the purifier to the boiler by closing said valves during the blow-off operation.
- 20 7. A water purifier of the class described having a horizontally arranged water inlet at the top of said purifier, a blow-off connection at the bottom of said purifier, a sediment receiving chamber of circular cross 25 section in the bottom thereof, a baffle plate immediately adjacent the inlet opening and extending from the top of said purifier to

the top of said chamber, whereby during the blow-off operation water impinges against said baffle plate and is directed downward to 30 cause sediment to be removed from end to end of said chamber through the blow-off connection.

8. A feed water purifier comprising a casing provided adjacent its top with a plurality of valved egress openings, and valved connections communicating with the casing interior said connections having funnel-like 35 inlets.

9. A feed water purifier comprising a casing provided adjacent its top with a plurality of openings, movable covers for some of said openings, valved pipes terminating in funnel-like extensions for other of said 40 openings, a coiled feed inlet connection for the casing and a valved funnel-like device 45 coöperative with said coil.

In testimony whereof, I have hereunto signed my name.
